US00D593535S

(12) **United States Design Patent**
Sheba et al.

(10) **Patent No.:** **US D593,535 S**
(45) **Date of Patent:** **** Jun. 2, 2009**

(54) **MEDIA PLAYER**(75) Inventors: **Yaron Sheba**, Mountain View, CA (US); **Derek T. Niizawa**, Sunnyvale, CA (US)(73) Assignee: **SanDisk Corporation**, Milpitas, CA (US)

FIG. 1 is a perspective view of a media player showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines, which define the bounds of the claimed design, form no part thereof. The broken lines showing environment are for illustrative purpose and form no part of the claimed design.
